MULTIPLE COIN SEPARATOR

Zygmunt S. Krysiak, 92 Harral Ave., Bridgeport, Conn.
Filed Feb. 10, 1959, Ser. No. 792,363
6 Claims. (Cl. 194—99)

This invention relates to a coin selector for telephones, dispensing machines, and similar devices, and has for an object to provide a simple and effective device which will separate good coins of the denominations of ten cents, five cents and twenty-five cents from spurious or bad coins, or so-called slugs.

It is also an object to provide a device of this character which will distinguish between and separate these coins of different sizes and values and discharge them through separate exits from the device for operating control of different coin-controlled apparatus.

Another object is to provide a device which will separate the different sizes and values of coins from all kinds of spurious or bad coins, such, for example, as coins of baser metals such as lead or brass, or coins containing iron or magnetic material, as well as discs of light metal or paper or like material, and will direct them into different chutes or similar passages for directing good coins to a coin-controlled mechanism, such, for example, as a telephone or article dispensing device, and to direct the spurious coins or so-called slugs to a separate container or to eject them from the machine.

Another object is to provide a construction of this character in which the good coins of the three different sizes and values are separated from each other and the spurious coins or so-called slugs by rolling action only of the coins along runways past various selecting devices.

Still another object is to provide a device of this character capable of separating the three coins of different sizes and values from each other and from spurious coins or slugs, which is devoid of bouncing anvils and pivoted deflectors or similar coin separating devices, so that the coins have a rolling motion only and the forward motion of the coins is controlled in the runways so that the velocity of the coins as they pass selecting devices along the various runways will attain a speed in accordance with that required for proper selection.

Still another object is to provide a device of this character which is of very simple construction and will occupy a minimum of space, so that it can be manufactured at relatively low cost and will not require a large space in the machine in which it is employed.

A still further object is to provide a device of this character in which there is no mechanism to be operated or shifted as a coin is inserted in the device to thus provide resistance to insertion of the coin, but the inlet opening is a free opening or passage permitting the coins to pass freely into the machine.

Still another object is to provide a device for separating these different values and sizes of coins from each other and from the spurious coins in which at no time is a coin or slug retained in the separator, requiring that it be later ejected or removed, but each passes directly through and is ejected from the device.

With the foregoing and other objects in view, I have devised the construction illustrated in the accompanying drawings forming a part of this specification. It is, however, to be understood the invention is not limited to the specific details of construction and arrangement shown, but may embody various changes and modifications within the scope of the invention.

In these drawings:

FIG. 1 is a front elevation of the device;

FIG. 2 is an edge view looking toward the left of FIG. 1;

2

FIG. 3 is a vertical section substantially on line 3—3 of FIG. 1;

FIG. 4 is a bottom edge view;

FIG. 5 is a detail longitudinal section;

5 FIG. 6 is a vertical section through the separating passage for dimes or ten-cent pieces, the plane of the section being substantially on the line 6—6 of FIG. 3;

10 FIG. 7 is a similar section through the selecting passage for five-cent pieces, the plane of the section being substantially on the line 7—7 of FIG. 3;

15 FIG. 8 is an edge view thereof looking from the right of FIG. 7;

FIG. 9 is a section through the passage for twenty-five-cent pieces, the plane of the section being substantially on line 9—9 of FIG. 3, and

15 FIG. 10 is an edge view looking from the right of FIG. 9.

The device shown in the drawings is designed to separate the three different sizes and values of coins 20 comprising a ten-cent piece or so-called dime, a five-cent piece or so-called nickel, and a twenty-five-cent piece or so-called quarter, from each other and from spurious coins or slugs of the same sizes or diameters. This device will separate legitimate coins of the three 25 sizes or values from various spurious coins of the same sizes made of other metals or alloys, such for example as copper, brass, lead, aluminum and so forth, or even paper discs, the spurious coins being generally called slugs. The coin selector is illustrated by itself, but it 30 will be understood it may be mounted in any suitable location in any machine or device to be controlled, such, for example, as a dispensing mechanism for various articles, which machine is not shown, telephones or other coin-controlled devices, the good coins of different sizes 35 and values being conducted or directed by any suitable means (not shown) to the respective mechanisms to be controlled or released, and the bad or spurious coins or slugs being kept from the controlled mechanism or devices and directed to any suitable container or ejecting 40 means (also not shown).

The device illustrated comprises an upright main or intermediate plate 1 having three openings 2, 3 and 4 therethrough, which openings are of different sizes, as shown in FIGS. 1 and 5, to accommodate the three coins

45 of different diameters, ten-cent, five-cent and twenty-five-cent pieces, and these three openings are arranged in succession, as shown in FIGS. 1 and 5, from a coin inlet opening 5 at the top and one edge of the machine. This opening 5 may be flared as shown to facilitate insertion 50 of the coins and may be formed in a flat tubular member 5a embracing the top edges of plates 1 and 6. A front plate 6 is secured to the forward side of the main plate 1 and spaced therefrom to provide a passage from the inlet opening 5 to the openings 2, 3 and 4. The

55 forward plate 6 is spaced from the main plate 1 by suitable separating means 7a and 8a forming runways 7 and 8 for coins inserted in the opening 5, the separator 8a being an inclined bar forming a runway 8 for rolling coins in the passage between the plates 1 and 6, and at the lower 60 edges of the openings 2, 3 and 4, which may be called coin selector openings. The runway 7 is the top edge of separator 7a between the plates 1 and 6. The runway 7 is above and forwardly of the runway 8 and located directly under the inlet opening 5 and above this runway,

65 and spaced somewhat from its discharge end is a light spring 9 located in the coin passage between the inlet opening 5 and the coin selector openings 2, 3 and 4. This light spring is an arcuately curved leaf spring having its concave side facing the inlet opening 5 and spaced a 70 distance from the runway 7 so that all coins or slugs running off the inclined runway 7 toward the runway 8 will deflect this spring backwardly, as indicated by the dotted

line position 9a. Light weight slugs, such as aluminum or aluminum alloy discs or paper discs, as indicated by the circles 10 of alternate dot-and-dash lines, will be deflected by this spring into a reject passage 11 formed on the front side of the plate 1 by an extension of the plate 6, which reject passage leads to a reject chute 12 formed with the plate 1 on the front side thereof by a flanged plate 13 which has its opposite edges bent inwardly forming spaced flanges 14, which spaces this plate from the plate 1 to form the reject chute. This spring may be adjustably mounted on one side of the plate 1 by a small plate 9b having an elongated slot 9c with a securing screw 9d. This permits locating of the spring in the best position for most effective action.

Also located at the free or inner end of the runway 7 is a fixed permanent magnet 15 which is so located that if the spurious coins 10 contain magnetic material they will be deflected to the left as viewed in FIG. 1, as they pass over this magnet and therefore will also be deflected into the reject passage and chute 11 and 12. These will keep all the light weight slugs and slugs containing magnetic material out of the selector passages for the legitimate coins and the slugs or spurious coins of heavier materials or metals, and thus prevent clogging of the legitimate coin passageways by the light weight or magnetic slugs. The magnet 15 may be mounted in the passageway between the inlet opening 5 and the coin select openings 2, 3 and 4 by any suitable means. In the arrangement shown it is located in an opening 16 in the plate 6 and extends across the passageway between this plate and the plate 1, and is removably retained in this position by a small metal plate 17 secured by the screw 18.

The three openings 2, 3 and 4 in the plate 1 are shown in FIGS. 1 and 5, located in succession or one after the other at one side of the inclined runway 8. They are of a size to permit the passage of the three different sizes of legitimate coins, as shown by the dotted lines, in FIGS. 1 and 5, a ten-cent piece or dime being indicated at 19 passing through the opening 2, a five-cent piece or nickel being indicated at 20 passing through the opening 3, and a twenty-five-cent piece or quarter 21 passing through the opening 4. It will be seen that the opening 2 is the smallest opening, the opening 3 of intermediate size, and opening 4 the largest, and they are arranged in a line or in succession, with the smallest opening 2 nearest the inlet opening 5. Therefore all coins rolling down the runway 8 go at least as far as the smallest opening 2. If the coin is a ten-cent piece or a slug of the same diameter as the ten-cent piece, it will pass through this opening 2, but if it is of a larger diameter it cannot pass through the opening 2 but must roll on to one of the succeeding openings 3 or 4. If it is the diameter of a five-cent piece or nickel it will pass through the opening 3, but if it is of the diameter of a twenty-five-cent piece it cannot pass through either of the openings 2 or 3, but must pass on to the largest opening 4, which will permit it to pass. Means is provided at the various openings to assist and direct the coins and slugs through the various openings 2, 3 and 4 corresponding to the different diameters. In the construction shown, the plates 1 and 6 are tipped or inclined backwardly, as shown in FIGS. 2 and 3, so that the coins rolling down the runway 8 are inclined backwardly, with their upper edges resting on the surface of the plate 1. Thus as they reach the various openings 2, 3 and 4 they will automatically tip into the openings of the proper size with their forward edges engaging the forward edges 2a, 3a and 4a of the respective openings, which, with the rearward inclination of the coins will act to deflect them through the respective openings. The first opening 2 is of a size too small to permit passage of the larger coins, five-cent and twenty-five-cent pieces, and the second opening 3 is too small to permit passage of the larger twenty-five-cent pieces. Therefore the five- and twenty-five-cent pieces rolling down the runway 8 must pass the opening 2 and the twenty-five-cent pieces must

pass the opening 3. The two runways 7 and 8 are inclined at the proper angle or pitch so that the coins rolling down the runway 8 will have the proper speed to pass into and through the proper openings and will not have sufficient speed to pass them.

Means is provided on the opposite side of the main plate 1 forming a passage from each opening 2, 3 and 4 for the coins passing through these openings to lead them to outlet openings for legitimate coins and reject openings for spurious coins, each passage leading to both a legitimate and a reject passage outlet. In each of these passages there is provided means for permitting the coins to roll through the passage and also means for separating legitimate rolling coins from the spurious coins or slugs of the same diameters and leading the good coins to the proper outlet opening and the slugs to the reject opening. These respective passages are shown in FIGS. 6, 7 and 9, the passage in FIG. 6 being for coins and slugs of the diameter of a ten-cent piece; the passage of FIG. 7 being for passage of coins and slugs of the diameter of a five-cent piece, and the passage of FIG. 9 being for coins and slugs of the diameter of a twenty-five-cent piece.

Referring first to FIG. 6, the ten-cent piece 19 passing through the opening 2 drops into a passage 22 formed at the rear side of the plate 1 by a third plate 23. Separating members 24 and 25 are located between the plates 1 and 23 to provide for the passage. As a coin the diameter of a ten-cent piece passes through the opening 2 it drops into the passage 22 onto an inclined upper edge 26 of the spacing element 24 which provides a runway for the coin. Legitimate ten-cent pieces are indicated by the full line circles 19, while slugs or spurious coins of the same diameter are indicated by dot-and-dash circles 28. As these coins roll down the runway 26 the drop through a continuation 22a of the passage 22 onto an inclined runway 29 on the top edge of the spacing element 25, during which the direction of movement of the rolling coins is reversed and their speed retarded in preparation for passing the poles 30 of a permanent magnet located in openings in the plates 1 and 23 on opposite sides of this passage and as shown in FIG. 6, just off the free end of the runway 29. If the coin is a legitimate ten-cent piece, as it has a high content of silver it is highly conductive for the magnetic field between the two poles of the magnets, generating sufficient induced electric current in the coin so that its motion is retarded and the coin will drop substantially straight downward from the end of the runway 29, as indicated by the full line circles in FIG. 6, and will pass out the legitimate exit opening 31. Spurious coins or slugs, having less electrical conductivity, will not be retarded sufficiently to pass out the opening 31, but as indicated by the broken dot-and-dash circles, will pass farther to the right and out the reject opening 32. There are also provided in the passage between the plates 1 and 23 and above the openings 31 and 32 adjustable deflectors 33 and 34 to assist in keeping the legitimate coins or slugs separated as they drop through the passage and to direct them to respective outlet openings 31 and 32. These deflectors are formed as lateral extensions of plates 35 and 36 adjustably secured on the outside of the plate 1 by suitable screws 37 in elongated slots 38 with the lateral extension extending through openings 39 and 40 in the plate, whereby the deflectors 33 and 34 may be adjusted to the proper positions for effectively deflecting the coins and slugs to their respective outlets 31 and 32. There may also be a deflector and separator 29 between openings 31 and 32 provided with inclined sides to help direct the coins and slugs to the openings.

The passage 41 for the five-cent pieces 20 and slugs of the same diameter is formed between the plate 23 and a fourth plate 42, there being spacing elements 43 and 44 between these plates to separate them to provide the

passage and also to provide rolling and guide means for the coins passing through the passage. As the five-cent piece or slug of the diameter of a five-cent piece passes through the opening 3 a lateral flange 45 in alignment with the bottom edge of the opening 3 directs it into the passage 41, where it drops onto an inclined runway 46 on the top edge of the separator 43, along which it runs to a downwardly extending portion 41a of the passage onto the inclined top edge 47 of the separator 44, which provides a further extension 41b for the passage between this edge 47 and the lower edge 43a of the separator 43. Located on the opposite sides of this passage at the exit from the portion 41b are the poles 48 of permanent magnets 49 located in openings in the plates 23 and 42 on opposite sides of the passage. As the five-cent pieces are made of an alloy which is a poorer conductor of electricity than the alloys of the spurious coin, these five-cent pieces 20 indicated by full line circles in FIG. 7 will pass freely between the poles of the magnet to a legitimate outlet opening 51, while spurious coins 52 of better conductivity, indicated by the dot-and-dash line circles, will be retarded and directed to the reject opening 53. To help separate the legitimate and the spurious coins, an adjustable deflector 54 as well as a triangular shaped deflector 55, may be provided in the passage between the outlets 51 and 53 and sufficiently above them to direct the spurious coins to their respective outlets.

The passage 56 for the twenty-five-cent pieces 21 and spurious coins of the same diameter leading from the opening 4 is provided by a fifth and back plate 57, which is separated from the plate 42 to provide this passage by separating elements 58 and 59 and also by laterally extending flanges 60 and 61, which extend across the passage at the outer edges thereof. As the twenty-five-cent pieces or spurious coins pass through the opening 4 they are directed by a laterally inclined flange 62 into the passage 56, this flange being located in alignment with the bottom edge of the opening 4 and passing over the edges of the plates 23 and 42. As these coins pass into the passage 56 they drop onto the upper edge 63 of the spacing element 58 down which they roll to a vertical connecting portion 56a of the passage onto the inclined top edge 64 of the spacer 59. This spacer forms a reverse extension 46b of the passage 56 between this edge 64 and the lower edge 58a of the spacing element 58. At the outlet of this extension of the passage and on opposite sides of the passage are the poles 65 of permanent magnets 49 and 49a located in holes in the plates 57 and 42. As the coins leave the extension 56b of the passage at the free end of the inclined runway 64 they pass between the two poles 65, and as the twenty-five-cent pieces 21, indicated by the full line circles, are made of an alloy containing a large amount of silver they have sufficient electrical conductivity so that as they pass through the magnetic field between the poles sufficient current is induced in these coins so that they are retarded and drop through the legitimate coin outlet 67, while spurious coins or slugs 68, indicated by the dot-and-dash line circles, of the same diameter of alloys or other metals of less conductivity, as they pass between the poles are not retarded sufficiently to pass through the outlet 67 but pass to and through the reject outlet 69. To further assist in separating the good from the bad coins an adjustable deflector 70 may be provided in the passage 56 above and between the openings 67 and 69, together with an inclined spacing element 71 below this deflector. This deflector may be a laterally extending end of the plate 72 adjustably secured on the back of the plate 67 by the screw 73, with the deflecting end 70 passing through an opening 74 in the plate. This permits setting of the deflector 70 at the proper location for proper directing of the legitimate and spurious coins to the outlet openings 67 and 69.

The magnets 49 and 49a providing the various pole pieces 30, 48 and 65 may be mounted on the outsides of

the plates 1 and 57, as shown in FIG. 3, and held there by any suitable means, such, for example, as sheet metal casings 75 secured to the plates by the end extensions 76 and screws 77. The various plates 16, 23, 42 and 57 may be secured together by any suitable means, such, for example, as the screws or bolts 78 and 79, which may also be used to secure the various separating elements between the plates in proper positions to provide the various passageways for the rolling coins.

It will be seen from the above that this device provides a simple and effective means for separating a plurality of legitimate coins of different values and diameters, such as the ten-cent, five-cent and twenty-five-cent pieces from each other and also from spurious coins or slugs of similar diameters, and will direct the legitimate coins to separate legitimate outlets from which they may be conducted by suitable means to various mechanisms which may be controlled by the separate coins, and that also the spurious coins or slugs, whether of heavy or light metal or light, nonmetallic material, as well as heavier slugs of base metals, or any magnetic material, are readily identified and directed to proper reject outlets so that they may be kept from the mechanisms to be controlled by the legitimate coins. Although the device illustrated has been shown as providing means for separating coins of three values and diameters, it will be understood the same mechanism and arrangement may be provided for separating the coins and slugs of two diameters and values. Thus it may be used for separating ten- and five-cent pieces, for ten- and twenty-five-cent pieces, or the five- and twenty-five-cent pieces, if it is desired to use the device with mechanisms responsive to the controls of these coins only.

Having thus set forth the nature of my invention, I claim:

1. A coin selector comprising an upright plate, means on one side of the plate providing a coin passage extending rearwardly from an inlet opening with a downwardly and rearwardly inclined runway at the lower part thereof, a second downwardly and rearwardly inclined runway in said passage spaced below the lower end of the first runway sufficiently to provide a reject chute between the runways, said plate provided with a plurality of openings therethrough over the second runway spaced rearwardly from the reject chute and of different sizes for passage of coins of different diameters, a depending light spring in the passage above the lower end of the first runway adapted to pass legitimate coins and heavier spurious coins from this runway onto the second runway but deflect light weight discs into the reject chute, a magnet at the lower end of the first runway positioned to deflect coins containing magnetic material from this runway into the reject chute, said openings in the plate arranged in succession along the second runway with the smallest nearest to the inlet opening with means at each opening for arresting rearward movement of and deflecting coins of different diameter rolling past them over the second runway through the respective openings, means at each opening of a size to prevent passage of coins of a diameter to pass through succeeding openings, means at the opposite side of the plate from the first passage providing a separate coin passage extending forwardly from each opening provided with a runway at the lower side thereof inclined downward in the opposite direction from that of the second runway so that the direction of movement of coins after passing through the respective openings is reversed from their direction of movement to the openings, said latter coin passages each leading to a legitimate and a reject outlet, and means associated with each passage from the openings in the plate free of coin bouncing anvils and pivoted deflector members to separate legitimate nonmagnetic from spurious nonmagnetic coins through rolling action only of the coins through said respective passageways and direct them respectively to the legitimate and reject outlets.

2. A coin selector comprising an upright plate, a second plate at one side of the first plate forming therewith a coin passage extending rearwardly from an inlet opening with a downwardly and rearwardly inclined runway at the lower part thereof, a second downwardly and rearwardly inclined runway in said passage spaced below the lower end of the first runway sufficiently to provide a reject chute between the runways, said first plate provided with a plurality of openings spaced rearwardly from the reject chute over the second runway of different sizes for passage of coins of different diameters and arranged in succession with the smallest opening nearest the inlet opening, a light depending spring in the said passage between the inlet opening and the other openings located over the lower end of the first runway adapted to pass legitimate coins and heavier spurious coins from this runway to the second runway but deflect light weight discs into the reject chute, a magnet at the lower end of the first runway capable of deflecting coins containing magnetic material from this runway into the reject chute, said plates being inclined laterally in a direction that coins moving along the second runway are inclined toward the openings over this runway and coins of different diameters pass through the respective openings according to size, plates on the opposite side of the first plate from said passage spaced to provide separate coin passages from each opening in the plate to a legitimate and a reject outlet, each of said latter coin passages leading from its respective opening in the first plate in a direction opposite to the direction of movement of coins along the second runway so that the movement of coins passing through the openings is arrested and then reversed, and means in each coin passage comprising a magnet capable of separating nonmagnetic legitimate and spurious coins passing through that passage by rolling action only and directing them to the respective legitimate and reject outlets from that passage.

3. A coin selector comprising an upright plate, a second plate at one side of the first plate forming therewith a coin passage extending rearwardly from an inlet opening with a downwardly and rearwardly inclined runway at the lower part thereof, a second downwardly and rearwardly inclined runway in said passage spaced below the lower end of the first runway sufficiently to provide a reject chute between the runways, said first plate provided with a plurality of openings over the second runway spaced rearwardly from the reject chute of different sizes for passage of coins of different diameters and arranged in succession with the smallest opening nearest the inlet opening, a light depending spring in the said passage between the inlet opening and the other openings located over the lower end of the first runway adapted to pass legitimate coins and heavier spurious coins from the first to the second runway but deflect light weight discs from the first runway into the reject chute, a magnet at the lower end of the first runway capable of deflecting coins containing magnetic material from this runway into the reject chute, means at each opening in the first plate to arrest forward movement of the coins of different diameters rolling past them in the passage and direct them through the respective openings, plates on the opposite side of the first plate from said passage spaced to provide a separate coin passage from each opening leading therefrom in a direction opposite to that of movement of the coins in the first passage so that the movement of coins through the respective openings is arrested and then reversed, downwardly inclined division walls in each of the latter coin passages forming connected oppositely inclined passageways one above the other and free of coin bouncing anvils and pivoted deflector members so the coins have a rolling action only through the passageways with the first passageway inclined from the associated opening in the first plate in the opposite direction from that of the second runway, a magnet forming a magnetic

field across the discharge end of the lower passageway of each coin passage to differentially retard rolling coins only of different electrical conductivity, and means forming separate discharge passages for said coins.

5. A coin selector according to claim 3 in which said first and second plates are inclined laterally over the second runway so the coins rolling along the second runway lean against the first plate and are inclined toward the openings for coins of different diameters to pass through the respective openings according to size.

6. A coin selector comprising an upright plate, means on one side of the plate providing with this plate a coin passage extending rearwardly from an inlet opening with a downwardly and rearwardly inclined runway at the lower part thereof, a second downwardly and rearwardly inclined runway in said passage spaced below and rearwardly of the lower end of the first runway providing a reject chute between the adjacent ends of the runways, said plate provided with an opening therethrough above and at one side of the second runway and spaced rearwardly from the reject chute for passage of coins from the second runway through the plate, a depending light arcuately curved leaf spring having its concave side facing said inlet opening disposed in the passage above the lower end of the first runway and adapted to pass legitimate coins and heavier spurious coins from the first to the second runway but deflect light weight discs into the reject chute and prevent them from passing to the second runway and the opening in the plate, a magnet at the lower end of the first runway positioned to deflect coins containing magnetic material from said runway into the reject chute, stop means at said opening in the plate for arresting rearward movement of the legitimate and heavier coins passing the spring to the second runway and deflecting them through this opening, means at the opposite side of the plate from the first passage providing a separate coin passage extending forwardly from the opening in the plate provided with a runway at the lower side thereof inclined downwardly in the opposite direction from that of the second runway so that the direction of movement of the coins after being arrested at the opening in the plate and passing through this opening is reversed from their direction of movement to this opening, means providing a legitimate and a reject outlet and a downwardly inclined coin passage from the lower end of the said latter runway to said outlets, said latter coin passage being free of coin bouncing anvils and pivoted deflector members for separating legitimate and spurious coins, and a magnet in said latter coin passage to separate legitimate nonmagnetic from spurious nonmagnetic coins through rolling action only of the coins through said passage and direct them to the respective outlets.

7. A coin selector comprising an upright plate, a second plate at one side of the first plate forming therewith a coin passage extending rearwardly from an inlet opening with a downwardly and rearwardly inclined runway at the lower part thereof, a second downwardly and rearwardly inclined runway in said passage spaced below the lower end of the first runway providing a reject chute between the runways, said first plate provided with an opening over the second runway spaced rearwardly from the reject chute for passage of coins, a light depending spring between the inlet opening and the other opening located over the lower end of the first runway adapted to pass legitimate coins and heavier spurious coins onto the second runway but arrest and deflect light weight spurious coins into the reject chute, a magnet at the lower end of the first runway capable of deflecting coins containing magnetic material from this runway into the reject chute, means at the opening in the first plate to arrest forward movement of the coins rolling along the second runway and direct them through this opening, a third plate on the opposite side of the first plate from the second plate providing a downwardly inclined coin passage leading from the opening in the first plate in a direction opposite to that of movement of the coins in the first passage so that

8

movement of the coins through this opening is arrested and then reversed, downwardly inclined guide means in the second coin passage providing connected oppositely inclined passageways one above the other free of coin bouncing anvils and pivoted deflector members so the coins have a rolling action only through these passageways with the first passageway inclined from the opening in the first plate in the opposite direction from that of the second runway, a magnet forming a magnetic field across the discharge end of the lower passageway to differentially retard rolling coins only of different electrical conductivity, and means forming a legitimate coin discharge passage and a spurious coin eject chute for said coins and to which they are respectively directed by said magnetic field.
